UNITED STATES PATENT OFFICE.

OTTO F. FOGELSTRAND, OF KENSINGTON, CONNECTICUT, ASSIGNOR TO HART MANUFACTURING COMPANY, OF SAME PLACE.

DESIGN FOR DOOR-LATCH.

Specification forming part of Design No. 5,503, dated January 30, 1872.

To all whom it may concern:—

Be it known that I, OTTO F. FOGELSTRAND, of Kensington, in the county of Hartford and State of Connecticut, have invented and produced a new and original Design for a Door-Latch, of which the following is a specification:

The nature of my design is fully represented in the accompanying engraving, to which reference is made.

A represents the handle; B, its plate; C, the latch-lift; D, its escutcheon; E, the latch proper; F, its escutcheon; and G, the catch.

The parts A, B, C are seen from the outside of the door when placed thereon in position for use, and the parts C, D, E, F, and G, from the inside.

Their ornamentation or configuration is fully shown in the accompanying engraving.

I claim as my invention—

The design for a door-latch, as shown.

OTTO F. FOGELSTRAND.
